GYRATING AND SHIFTABLE PIVOT WINDOW WITH STATIONARY WEATHER BARS

John P. Travis, Dallas, Tex.

Application May 25, 1955, Serial No. 510,991

6 Claims. (Cl. 20—53)

My invention relates to a pivotally mounted and laterally shiftable window sash and more particularly to a window sash mounted in the grid of a facade of a building and in which the sash may be rotated through an arc of approximately thirty degrees.

One of the principal objects of the invention is to provide a window in which the sash may be shifted laterally and inwardly of its opening and then rotated either clockwise or counterclockwise an amount to allow both side faces of the sash to be cleaned or serviced.

Another object of this invention is to provide a window which may be cleaned and repaired on both side faces without the use of scaffolding.

A still further object of this invention is to eliminate the necessity of a window frame, the window sash being supported by and engaging directly upon the grid structure of a building facade.

A further object of this invention is to provide the grid structure which serves as a frame for the window sash with means to seal directly thereagainst when in its closed position.

Other objects of the invention will appear hereinafter throughout the specification.

Referring to the drawings:

Figure 1 is a horizontal section through my improved window construction taken on a plane just above the top edge of the window sash when the window is closed.

Figure 2 is a view similar to Figure 1, but showing the window sash shifted laterally inwardly into a position where it may have a restricted rotation in either a clockwise or a counterclockwise direction.

Figure 3 is a view similar to Figure 2 but showing the window sash rotated approximately thirty degrees in a counterclockwise direction, its position when rotated in a clockwise direction being indicated by dotted lines.

Figure 4 is a view in side elevation, with parts broken away, of the inside of the window when in its closed position.

Figure 5 is a horizontal section through one of the jamb portions of a grid and the adjacent portions of the window sash and a spandrel unit.

Figure 6 is a vertical section through my improved window with the window sash in closed position and showing parts of the facade structure adjacent the window.

Figure 7 is a detail view in elevation showing a portion of the window sash, the window sill, and the lower link arrangement which connects the sash to the sill and allows the sash to move laterally inwardly away from the grid.

Figure 8 is a horizontal section on the line 8—8 of Figure 7 showing the top side of a portion of the lower link arrangement.

Figure 9 is a vertical section on the line 9—9 of Figure 7 showing the link pivot connection between the sash and the sill.

Referring to the drawings, 1 represents an opening in the grid 2 of a facade of a building in which a window sash 3 is pivotally mounted and laterally shiftable by

2

means of two pairs of pivotally connected links at both the top and the bottom of the opening 1. Since the link arrangement at the sill 4 is the same as that at the head 5 of the opening only one will be described. The link arrangement at the head 5 is merely turned upside down with respect to the one at the sill 4. Each link arrangement comprises a first pair of links 6 and 7 pivoted together at one end and to the sill 4 by a pivot 8, and a second pair of links 9 and 10 pivoted to the other ends of the first pair by the pivots 11 and 12, and to the lower edge of the sash 3 by the pivot 13. The pivot 13 is located midway between the side edges of the sash, and the pivots 11 and 12 are located approximately midway between the ends of the links 9 and 10.

15 When the sash is in its closed position it engages the inner face of the jamb portions 14 at the sides of the opening, and when it is desired to open the window the sash is moved inwardly to the position of Figure 2 from which position it may be rotated a limited amount

20 until one of its side edges strikes the stationary weather bars 15 and 16 which are integral with the grid and project toward each other into the opening 1. The sash may be rotated in either direction from the position of Figure 2. When in the solid line position of Figure 3,

25 the right half of the outside face of the sash may be cleaned or repaired, and when in the dotted line position the other half of the outside face is accessible for cleaning or other servicing. After the sash has been cleaned or otherwise serviced, it may be pushed back against the sealing members 17 and 18 on the stationary bars and the jamb portions, respectively. In this position all 30 of the links will be arranged in the plane of the sash.

As shown in Figures 1, 2, 3, 5, 6 and 9, the grid 2 is of generally hollow channel form in cross section but any 35 other suitable form of cross section may be used. Also Figures 1, 2, 3 and 5, show fins 19 projecting outwardly from the grid structure but such fins are not necessary in the operation of the window.

Spandrels 20 are shown in the grid openings adjacent 40 the window but it will be understood that some or all of these could be replaced by windows, if desired.

The term "facade" used in this application is intended 45 to cover any frame, panel, building face unit, or other structure that may be used to mount a window and/or panel in the side of a building.

While the improved window disclosed herein is shown and described as having its sash mounted on vertically disposed pivots, it is apparent that it could be mounted on horizontally disposed pivots, if desired. Moreover, 50 while the improved window disclosed herein is shown and described as having a sash mounted so as to pivot inside, it is apparent that it could be mounted so as to pivot outside of the building upon which it is mounted.

Plates 21 may be used to cover the links when in their 55 collapsed position, as shown in Figure 6, if desired.

As shown in Figures 6, 7, 8 and 9, felt strips 22 are mounted in the top and bottom edges of the links 9 and 10 and engage the adjacent edges of the sash to aid the 60 stationary weather bars in sealing the top and bottom edges of the sash.

The free ends of the links 9 and 10 bear on the sill 4 and the head 5 of the opening in the grid and serve to stabilize the sash in its movement to and from a closed position.

65 A stop screw 23 is adjustably mounted in the end of each of the links 6 adjacent pivot 8 and projects slightly beyond said end to engage a flattened portion 24 on the adjacent end of the link 7 to limit clockwise movement of the link 6 with respect to the link 7 as the sash is moved inwardly to the position of Figure 2.

A drip plate 25 is secured to the sash 3 adjacent its

lower edge and covers the joint between the sash and the stationary weather bar 16.

The above description and drawings disclose a single embodiment of the invention, and specific language has been employed in describing the several figures. It will, nevertheless, be understood that no limitations of the scope of the invention are thereby contemplated, and that various alterations and modifications may be made such as would occur to one skilled in the art to which the invention relates.

I claim:

1. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said second pair being pivoted to the links of said first pair at points equidistant from the adjacent aligned pivot, and stationary weather bars at the sides of said opening to which the closure is pivoted.

2. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said first pair being pivoted to the links of said second pair at points equidistant from the adjacent aligned pivot, and stationary weather bars at the sides of said opening to which the closure is pivoted, said weather bars being located on the outside of said closure and spanning the joint between said closure and the adjacent sides of said opening.

3. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said first pair being pivoted to the links of said second pair at points equidistant from the adjacent aligned pivot, and stationary weather bars at the sides of said opening to which the closure is pivoted, said weather bars being located on the outside of said closure and spanning the joint between said closure and the adjacent sides of said opening, said

weather bars extending entirely across said opening and being located one at each of the pivoted sides of the closure.

4. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said first pair being pivoted to the links of said second pair at points equidistant from the adjacent aligned pivot, and stationary weather bars at the sides of said opening to which the closure is pivoted, said closure being a window sash.

5. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said first pair being pivoted to the links of said second pair at points equidistant from the adjacent aligned pivot, and stationary weather bars at the sides of said opening to which the closure is pivoted, said weather bars being located on the outside of said closure and spanning the joint between said closure and the adjacent sides of said opening, said closure being transparent, and said weather bars being integral with said facade element.

6. A closure construction comprising a facade element, a rectangular opening in said facade element, two opposite sides of said opening constituting jamb portions for a closure, a closure for said opening engaging said jamb portions when in its closed position, aligned pivots one on each of two opposite side edges of said closure, said pivots being positioned centrally of said opposite side edges of said closure, a first pair of links of substantially equal length at each of the two remaining sides of said opening, the links of each of said first pairs of links being pivoted together at one end and to a side of said opening by the same pivot means, a second pair of links at each of said remaining sides of said opening, said links of each of said second pairs of links being pivoted together at one end and to said closure by the adjacent one of said aligned pivots, and the other ends of the links of said first pair being pivoted to the links of said second pair at points equidistant from the adjacent aligned pivot, and stationary weather bars at the sides of said opening to which the closure is pivoted, said weather bars being arranged one at the top and one at the bottom of said opening.
